HOODED CYLINDER HEAD FOR GAS ENGINES

Robert S. Moore, Silver Spring, Md., assignor to
 General Airmotors Company, Scranton, Pa., a
 corporation of Pennsylvania

Application November 30, 1932, Serial No. 645,093

1 Claim. (Cl. 123—90)

The invention relates to new and useful improvements in gas engines and more particularly for a gas engine having a cylinder head attached to the cylinder body and provided with supporting and operating means for the intake and exhaust valves thereon.

An object of the invention is to provide a cylinder head with a protecting hood covering the rockers controlling the intake and exhaust valves, which protecting hood is formed integral with the cylinder head and provided with fins which aid in the dissipating of the heat generated in the cylinder.

A further object of the invention is to provide a hooded cylinder head of the above type wherein said hood has a streamline shape so as to insure that the air passing over the same will contact with the surface of the hood for the efficient cooling of the same.

20 In the drawings:

Fig. 1 is a sectional view through the upper portion of a cylinder and through a cylinder head with the improved integral hood covering and housing the rockers and the intake and exhaust valves operated thereby.

Fig. 2 is a plan view of the same.

The invention as shown in the drawings is applied to a gas engine which includes a cylinder 1, having a seating end or face 2 provided with an exhaust opening 3 and two intake openings, one of which is indicated at 4, in Fig. 1, and both of which are shown in the plan view in Fig. 2. Attached to the cylinder is an aluminum alloy head 5. This head has its lower end machined so as to closely fit the outer face of the cylinder head and is often referred to as a poultice head. This type of engine is shown, described and claimed in my prior Patent 1,820,475, granted August 25, 1931, and further description of the poultice head and the attaching of the same to the cylinder is not thought necessary.

Mounted for movement in the head 5 of the cylinder is the stem 6 of the exhaust valve 7, which controls the exhaust port in the end of the cylinder. Springs 8 surround the stem and normally hold the valve closed. There is a valve 9 for each intake opening carried by a valve stem, one of which is indicated at 10. The valve stems are mounted in the cylinder head and associated with each valve stem is a spring 11 which normally holds the valve closed. The arrangement of two intake ports with valves simultaneously controlling the same and one exhaust port with a valve controlling said ex-

haust port forms no part of the present invention, but is shown, described and claimed in my copending application 402,703, filed October 26, 1929. The intake and exhaust valves are controlled by rockers. The intake valve operating rocker is indicated at 22. This rocker is in the form of a yoke having two arms 23, 23, which are connected to the valve stems. There is a third arm 24, which is connected to a rod 25 for imparting oscillations to the rocker. The exhaust valve is controlled by a rocker 26 which includes an arm 27 bearing on the valve stem and an arm 28 connected to a rod 29 by which oscillations are imparted to the rocker 26. These two rockers 22 and 26 are mounted on 15 the same supporting shaft 30 but for independent rocking movement thereon. This shaft 30 is carried by a bracket 31. The bracket 31 is provided with projecting trunnions engaging bearing blocks 32, 33, which are secured to 20 the cylinder head by a bolt 34. A plate 35 is attached to one of the cylinder head bolts 36 and this plate has an upturned lug 37 which lies between yoke arms of the bracket 31. A bar 37a attached to the outer end of the bracket 25 31 is also attached to the crank casing at its lower end. This forms a rocker assembly which is secured to the cylinder head by a single bolt 30 and to the crank casing and the entire assembly can be readily removed from the cylinder head. 30

The present invention has particularly to do with a protecting hood for the valve rockers and the valve stems, which hood is formed as an integral part of the aluminum alloy poultice head. Said hood includes a vertical wall 15 35 which extends above the valve stems and the rockers and is provided with a top portion 16. This top portion 16 is preferably made separate from the body portion of the hood and is secured thereto by bolts, one of which is indicated at 16a. The hood extends beyond the end of the rockers and completely covers and houses said rockers, the valve stems and the springs associated therewith. The vertical wall 15 extends all the way around the hood. This 45 vertical wall as clearly shown in Fig. 2, is given a streamline shape. The engine is mounted so that the air currents are in the direction of the arrow in Fig. 2, said vertical wall of the hood in the region where the air stream first 50 impinges on the same, is provided with horizontally extending fins or ribs 17. There are a series of these fins and they are preferably of graduated extent, with the longest fin at the lower end of the hood. These fins extend from 55

the point 18 around the end of the hood to the point 19, said fins might be extended all the way around the hood but they are most efficient in the region in which they have been placed. The cylinder head is also provided with horizontally extending fins 20 and likewise the cylinder has horizontally extending fins 21. The heat created within the cylinder is rapidly transmitted to the cylinder head and to the hood attached thereto. The hood being integral with the cylinder head greatly aids in the dissipation of the heat. The fins on the hood and cylinder head further aid in the cooling of the cylinder. The hood having a streamline shape will aid throughout its entire extent in the dissipation of the heat. The hood also serves as a means for covering the valve rockers, valve stems and associated springs so as to protect the same from dust. The hood overhangs the side of the cylinder and provides a space through which access may be readily had to the rocker assembly. The operating devices for the rocker assembly and the supporting bar for the bracket extend downward through the opening in the underface of the overhanging portion of the hood.

It is obvious that minor changes in the construction of the integral hood and the shaping

of the same may be made without departing from the spirit of the invention as set forth in the appended claim.

I claim:

A gas engine including in combination, a cylinder, a head secured thereto, said cylinder head having two intake ports and one exhaust port disposed close to each other, a valve for controlling each port, said valves being movable in lines parallel with each other, a rocker mounted on the cylinder head for operating said intake valves, a rocker mounted on said cylinder head for operating said exhaust valve, a single hood formed integral with the cylinder head and covering and housing said rockers, said hood having a vertical wall extending from the cylinder head above the rockers and covering and enclosing said rockers, said vertical wall having integral fins projecting therefrom for dissipating the heat generated in the cylinder, said hood having a streamline shape and symmetrically disposed relative to the direction of the air currents contacting with the hood, said fins being disposed at the side thereof with which the air contacts and merging into said vertical wall at the opposite side of the cylinder. 5 10 15 20 25
